HOLDER FOR BRUSHES OR THE LIKE

Pincus J. Harris, Rye, Port Chester, N.Y., assignor to Empire Brushes, Inc., Port Chester, N.Y., a corporation of New York

Filed Oct. 20, 1969, Ser. No. 19,632

Term of patent 14 years

Int. Cl. D7—99

U.S. Cl. D44—29

FIG. 1 is a front elevational view of a holder for brushes or the like embodying my new design;

FIG. 2 is an end elevation thereof;

FIG. 3 is a top plan view thereof;

FIG. 4 is a cross-sectional view taken on line 4—4 of FIG. 1;

FIG. 5 is a cross-sectional view taken on line 5—5 of FIG. 1; and

FIG. 6 is a rear elevational view thereof.

I claim:

The ornamental design for a holder for brushes or the like, substantially as shown.
